UNITED STATES PATENT OFFICE.

FREDERICK W. HEDGELAND, OF CHICAGO, ILLINOIS, ASSIGNOR TO THE
W. W. KIMBALL COMPANY, OF SAME PLACE.

STOP-ACTION FOR ORGANS.

SPECIFICATION forming part of Letters Patent No. 664,858, dated January 1, 1901.

Application filed October 20, 1898. Serial No. 694,067. (No model.)

To all whom it may concern:

Be it known that I, FREDERICK W. HEDGELAND, a citizen of the United States, residing in Chicago, in the county of Cook and State 5 of Illinois, have invented a new and useful Improvement in Adjustable Combination Stop-Actions for Organs, of which the following is a specification.

This invention relates to the construction 10 of adjustable combination stop-actions for pipe-organs and is an improvement on previous constructions thereof.

The nature of the improvement is fully set forth below and also illustrated in the accompanying drawings, in which—

Figure 1 is a longitudinal vertical section, and Fig. 2 a plan, of the invention. Figs. 3 and 4 are detail sections of the wipers, showing them in different positions. Fig. 5 is a 20 section of the wipers, showing the parts in the same position as Fig. 3, but taken on a different line. Figs. 6 and 7 are sections similar to Figs. 3 and 4, showing still other positions. Fig. 8 is a partial side view of one of 25 the locking-bars.

In the drawings, A and B represent two stop-rods of an organ and may serve as types of the series of rods used therein. They are 30 operable at will by the organist in the usual manner. They are each provided with a stud or arm A', through which they may be controlled by the other devices hereinafter described and forming the subject-matter of my present invention.

Arranged transversely of the series of stop-rods is a pair of wipers C and D, each carrying a series of adjustable pins acting on the studs A' of the stop-rods, the pins in wiper C being indicated at E and those in wiper D at F. The pins are inserted in sockets formed 40 in the opposing sides of the wipers, and each is provided with a spring G, tending to force it outward. Each pin is also provided with a collar G', which engages the shoulder G² of its socket and limits the action of the spring. Each pin, furthermore, is notched or grooved 45 at two points G³ and G⁴, and these notches or grooves are adapted to receive locking-bars H and J, arranged longitudinally of the 50 wipers, the bar H acting on the pins in wiper C and the bar J on those in wiper D. The

bars are movable at the will of the organist, are normally in their locking positions, and are preferably supported by pivoted arms or U-shaped bearings H' J', so that they may be 55 carried into and out of action by an endwise movement imparted through connections H² and J² and levers H³ J³. A spring H⁴ is employed with each locking-bar to keep it normally in action.

The pins in one wiper are, it will be noticed, arranged opposite to those in the other wiper, the opposite pairs thereof acting on the same stop-rod, and they have two positions—namely, an outermost position (shown in the 65 case of one pin E and one pin F in Fig. 2) and an inner or retired position (shown by the other pins in the same figure)—and they may be locked in either of these positions by the locking-bars, inasmuch as one or the other 70 of the notches in the pins is always in position to receive the bars. It is also a peculiarity of the pins that when the wipers are closed only one of any pair of pins is in its outer position, both pins never occupying 75 either the "out" or the "in" position at such times. The wipers are also movable toward or away from each other at the will of the organist through suitable operating devices—such, for instance, as the centrally-pivoted lever K and the connecting-rod K', joining said lever to wiper C, and rod K², joining the lever to wiper D. One or the other of these rods is preferably extended, so it may serve 80 as a means for operating lever K and so it 85 may be within reach of the organist. Either rod may, however, effect a junction with a button, puli, or treadle operable by him. In either case he applies the power necessary to move the lever in the direction desired and 90 moves the wipers simultaneously either toward or away from each other. At Figs. 1, 2, 4, and 7 the wipers are shown as having been separated to the limit of their movement (this being their normal and non-acting 95 position) and at Figs. 3, 5, and 6 as having been brought together. It is only when they are being brought together that they move the stop-rods. In these movements the wipers are guided by upper and lower guides L and M. 100

With the construction described the operation is as follows: Supposing the organist

desires to set a combination, he first moves the wipers together or into their near relative position. In so doing such of the pins as happen to be in their outer positions will 5 reverse their corresponding stop-rods, those of the rods which were out being carried to their in positions and those which were in to their out positions. Thus, referring to Fig. 2, if the wipers are brought together it 10 will be seen that it must cause the reversal of the two stop-rods there shown, carrying rod A out and rod B in. The organist now raises the lock-bars H and J and releases all the pins, and the latter are immediately forced 15 outward by their springs so far as the studs A' will permit. He then while retaining the lock-bars out of action pulls out such of the stops as he desires to include in the combination which he is setting, moving them in the 20 direction of the arrow shown upon rod A in Fig. 2, and at the same time he pushes in such stops as are then out, but which he does not wish to include in the combination. In so doing the pins in wiper C belonging to the included stops are carried by the studs A' of those stops to their inner positions in the wiper and the pins in wiper D belonging to the same stops are given opportunity by the outward movement of the stop-rods and studs 25 to move to their outer positions in said wiper. By the pushing in of the out stops not included in the combination the pins in wiper C of such stops are allowed to move to their outer positions and those in wiper D are carried inward. The pins belonging to the stops 30 which were already in at the time of commencing the setting operation and which are not included in the combination will be in the same positions as those of the pushed-in stops above described. The organist now lowers the locking-bars and locks the pins and then separates the wipers and pushes in the stop-rods which at a previous stage he had pulled out. This completes the setting 35 operation and leaves the stop-rods free to be moved without affecting the wiper-pins. The combination may be thrown into action at any time by again bringing the wipers together and through the medium of the out pins in 40 wiper D throwing out the rods of the stops embraced in the combination. As shown at Fig. 2, the stop A and its pins are in the position they will be left by the setting on the supposition that that stop is included in the 45 combination, and it will be seen that the bringing of the wipers together will move the stop out, so it must go into action with the other stops of the combination. In the same figure stop B is shown as being already out, 50 and its pin E will necessarily throw it in when the wipers next close.

In Fig. 3 I have shown the wipers as being together, with the stop-rod shown in the front of the figure in its in or non-acting position, 55 while the stop carrying the rear stud A' is in its out or acting position.

Fig. 4 shows that the wipers have been

opened and the pins all released preparatory to setting.

In Fig. 5 the wipers are shown as again 70 closed, with the stops in the same position as in Fig. 3, this change forcing the pin F of the foremost stop into its socket. If the lock-bars are now lowered, pin F will be locked in this position. 75

Fig. 6 shows a stop included in the combination and the wiper-pins belonging to it in the positions occupied by them after setting. Fig. 7 shows the same parts with the wipers 80 opened preparatory to resetting.

It will be understood, of course, that any convenient number of my adjustable combination-actions may be used, each being wholly independent of the others.

It will ordinarily be the case that of the stop-operating pins one pin of every pair will be in its inner position, so that the wipers can close without hindrance; but if at the time of commencing to set a combination both series of pins are out then before moving the wipers 90 together the pins should be released from the lock-bars, so as to leave them free to be moved into their sockets by the studs on the stops. 85

I claim—

1. The combination with a series of stop-rods, of a pair of wipers arranged transversely and movable over the rods, and adjustable devices carried by the wipers and adapted to be set so as to operate the rods, substantially as specified. 95

2. The combination with the series of stop-rods, each having an engaging device such as A', of two series of pins adapted to be set so as to operate the rods by means of said device, movable supports for said pins, independent 105 of the rods, and means for operating said supports, substantially as specified.

3. The combination in an organ, with the stop-rods, of two series of pins adapted to be set and acting to operate the rods, two separate movable supports for said pins, one for each series, and means for operating said supports, substantially as specified. 110

4. The combination in an organ with the stop-rods, of wipers movable back and forth 115 longitudinally of the rods, two series of adjustable pins carried by the wipers and engaging the rods, and a locking device on each wiper for locking the pins on the same, substantially as specified. 120

5. The combination in an organ, with the stop-rods having projections such as A', of movable wipers arranged across the rods, adjustable pins for operating the rods and carried by the wipers, and lock-bars for locking 125 the pins in their adjusted positions, substantially as specified.

6. The combination with the stop-rods, of the wipers, the pins carried in the wipers, the springs acting on the pins, and means for locking the pins in their set positions in the wipers, substantially as specified. 130

7. The combination in an organ, with the stop-rods having projections such as A', of

movable wipers arranged across the rods, adjustable pins for operating the rods and carried by the wipers, springs acting upon the pins, and lock-bars for locking the pins in their adjusted positions, substantially as specified.

8. The combination in an organ, with the stop-rods, of movable wipers carrying adjustable pins engaging the rods, individual springs acting upon the pins, and the lock-bars for locking the pins in the wipers, substantially as specified.

9. The combination in an organ, with the stop-rods having means for engaging the devices whereby they are operated, of a pair of wipers arranged across the rods and movable toward each other, adjustable operating-pins upon the proximate faces of said wipers and each having two positions therein, and means for locking said pins in their adjusted positions in the wipers, substantially as specified.

10. The combination in an organ, with the stop-rods having means for engaging the devices whereby they are operated, of a pair of wipers arranged across the rods and movable toward each other, adjustable operating-pins

upon the proximate faces of said wipers and each having two positions therein, springs acting outward on said pins, and means for locking said pins in their adjusted positions 30 in the wipers, substantially as specified.

11. The combination stop-action having a pair of wipers and mechanism whereby the organist may move the same bodily back and forth over the rods, and adjustable devices 35 mounted on the wipers and engaging fixed projections on the rods, and serving to move the latter with the wipers, substantially as specified.

12. The combination stop-action for organs 40 having wipers such as C and D, movable bodily back and forth over the stop-rods, and also having the devices which are set, and by which the stops are included in or excluded from the combination, carried part by one 45 wiper and part by the other wiper, substantially as specified.
